UNITED STATES PATENT OFFICE.

WRAY FALWELL, OF FITCHBURG, MASSACHUSETTS, ASSIGNOR TO BROWN BAG FILLING MACHINE COMPANY, OF FITCHBURG, MASSACHUSETTS.

SLED.

1,299,444.

Specification of Letters Patent.

Patented Apr. 8, 1919.

Application filed January 25, 1917. Serial No. 144,487.

To all whom it may concern:

Be it known that I, WRAY FALWELL, a citizen of the United States, residing at Fitchburg, in the county of Worcester and State of Massachusetts, have invented certain new and useful Improvements in Sleds, of which the following is a specification.

The invention has for an object to enable the flexing of a sled runner with less effort than has been required heretofore in flexible runner sleds. Another object is to enable the production of a greater curvature in such runners with the use of the same steering connections heretofore employed. A further object is to give a construction of runner and mounting which will produce a banking effect at the same time that the runner is flexed. Another important purpose is to give such construction in flexing runner sleds that the runners will more efficiently return to normal position aligned with the mean direction of the deck of the sled. A further object is to enable the attainment of these objects without a material departure from the structural details of sleds as at present manufactured, but utilizing stock material in a new arrangement and relation whereby the new results are attained.

Additional objects, advantages and features of invention will appear from the construction and arrangement and combination of parts comprising one of the possible embodiments of my invention, hereinafter described and shown in the drawings, wherein, Figure 1 is a bottom view of the sled in normal position.

Fig. 2 is a similar view of the sled in turning position.

Fig. 3 is a side view of the sled,

Fig. 4 is a front view thereof in turning position,

Fig. 5 is a bottom view showing a means for positively returning the parts to normal position, resiliently,

Fig. 6 is a fragmentary side elevation showing a modification of the runner construction,

Fig. 7 is a cross section of the sled,

Fig. 8 is a cross section of the runner at its super-flexible portion.

Fig. 9 is a detail cross section of the connection between the runner and leg of the standard,

Fig. 10 is a detail cross section of the runner,

Fig. 11 is a lateral elevational detail of a modified form of connection between the front and rear runner sections,

Fig. 12 is a bottom view of the construction of my invention where four legs are required,

Fig. 13 is a side elevation thereof,

Fig. 14 is a cross sectional detail of a form of runner,

Fig. 15 is a detail of the manner of attachment of the intermediate legs to the body in the last mentioned modification.

There is illustrated a sled comprising runners 10 upon which there is mounted a plurality of longitudinally spaced benches 11, these including the standards 12 having divergent leg portions 13, upon which rest the bars or bolsters 14. Upon the bolsters the usual deck 15, and short side raves 16 are mounted, the latter being on the outer ends of the bolsters 14. The deck and raves are also provided with a cross bar 17 immediately of the body of the sled, secured upon the underside of the deck, this bar being similar in form to the bolsters 14. The runners may be curved upwardly at their forward parts in accordance with the usual practice in the construction of flexible runner sleds, and if desired the raves 16 may be extended and secured pivotally to the upper ends of the runners, in accordance with the customary practice, although not so shown in the present instance, as I prefer for the sake of economy and other reasons to employ at each side a link 18 comprising simply a piece of strap metal pivoted upon the bolt 19 by which the forward end of the rave is secured upon the forward bolster 14, the forward end of the link 18 being secured flatly upon a cross bar 20, the forward end of each runner being formed with an ear 21 disposed flatly against the underside of the bar 20, the link 18, bar 20, and ear 21 at each side being pivotally secured by a single bolt 22 holding them snugly together. The deck

includes the usual middle stave 28, elongated at its forward end to provide an anchorage stem 24, upon which is pivoted the rear ends of a steering lever 25 having a longitudinal slot 26 in its forward end receiving slidably the headed bolt 27 fixed centrally in the bar 20. The lever 25 is formed as usual of two plates, between which the steering bar 28 is secured, having its ends projected beyond each side of the sled to receive the feet of an operator thereagainst, or to be manipulated, as desired.

The knees or standards 12 are of a familiar construction in which the top portion 29 is provided closely adjacent the outer edge with a pivot aperture having the bolt 19 engaged therethrough, and adjacent the inner part provided with a slot 30 concentric with the pivot opening at the outer side having bolts 31 engaged loosely therein. Contrary to general practice in the construction of such sleds, the standards at both front and rear are provided with the slots 30 so that both the front and rear standards may rotate upon a vertical axis, which, in association with other details of construction to be described enables a new action in runners of this character and with the type of steering connection shown.

In the action of the sled as will be subsequently apparent, when a turn is made the runners are tilted toward the axial center upon which the turn is made, at their upper parts, and by the form of connection described between the upper ends of the runners and the bar 20, the bar becomes flexed as shown in Fig. 4, the resiliency of the bar 20 serving to aid very materially in return of the parts to normal position when the steering bar is released from stress.

What may be termed the foot portions 32 of the legs are bifurcated as usual, but, contrary to usual construction in such devices are not riveted rigidly upon the runners, but are extended divergently, the central or stem flange 33 of the runner engaging snugly in the crotch between the furcations, the attaching bolts 34 by which the runners are secured to the feet being riveted firmly in the feet, these bolts being fitted snugly in the apertures of the feet. The apertures in the runner, however, through which the bolts extend, in each instance, is made much larger than the bolts so that the runner is free to have a rocking movement laterally until checked by the furcations, so that the runner may be tilted to present its lower face laterally in one direction or the other, and away from the normal position. In such movement the upper edge of the runner rests at all times snugly in the crotch as before stated, so that ample support is secured. By reason of the customary bending of the foot portions longitudinally of

the runner and away from each other, as shown at 35, it will be seen that the bearing between the foot 32 and the runner is quite extensive, and that the support does not occur solely between the extreme edge portion in the crotch and the upper side of the runner, which would tend to produce excessive wear. By this form of mounting of the runner, when the steering bar 28 is turned and the upper end portion of the runners are pressed laterally, the runners are free to turn, and it will be seen that the direction of this turning movement is such that the sides of the runners toward the inside of the curve produced are turned downward, so that a full banking effect is produced, as clearly indicated in Fig. 4. It is thought desirable also to bend the inner edge of each runner downwardly, slightly, as shown at 36, see Figs. 9 and 10, this edge being moved farther downward at the outer side of the sled with respect to a turn when being made, which by reason of the fact that the weight of the rider is thrown upon that side, makes the hold of the device upon glacé snow, or ice highly efficient. However, it will be apparent that even with a plain T-section runner the device will produce a highly efficient banking effect. A hollow ground runner shown in Fig. 14, may be used to good effect, also.

Intermediately of the length of the runner, over a portion thereof which I prefer to locate approximately in line with the middle of the deck, although this exact location is not arbitrary, the lateral flanges at the lower side of the runner are cut away, or the runner otherwise formed without the flanges, for a distance of several inches, more or less, as shown at 40, Figs. 1 and 2, and as clearly apparent in the enlarged cross section of the runner Fig. 10. By this construction in the runner, when the steering bar 28 is operated the runners flex with great ease, especially over the portion 40, resulting in the disposition of practically the entire rear section 41 of the runner at an angle to the longitudinal medial line of the sled corresponding to the direction of the rear bowed part of the portion 40, while practically the entire front portion of the runner extends at an angle to the longitudinal medial line of the sled corresponding to the direction of the forward part of the portion 40, whereas in a runner of the same cross sectional dimension throughout its length, only the rearmost and foremost parts 120 of the runners would have such direction, while the intermediate portions would be directed at much lesser angles to the longitudinal medial line, so that the turning efficiency of the sled to corresponding degree of movement in the steering connection would be much less than is the case where my improved construction is employed.

My construction enables the user to produce an angle between the opposite end portions of the runner much greater than the angle between the end portions of T-section 5 runners mounted in accordance with the usual practice (as illustrated in the patent to Allen # 797,338). In my device the radius in which the end portion of the runner is moved by the steering connection corresponds to the distance between the forward 10 end of the runner and the pivot bolt 19 in the foremost bolster, whereas in the prior construction the radius of such movement corresponds to the distance between the forward 15 end of the runner and the rearmost point of rigid connection between the runner and the deck. This radius in prior devices would ordinarily not be less than twice the radius of movement in my sled, and ordinarily 20 much greater than that.

By the employment of my invention it is possible to utilize a cheap steel for the construction of the major portion of the runners, while yet retaining the full advantage of a high grade steel in the flexing portion, as shown in Figs. 11, 6, where the rear section 41 and front section 42 of the runner are formed separately, the front end of the rear section stopping short of the rear end of the 30 front section a distance of several inches. A spring section 43 is provided, connecting the adjacent ends of the runner sections, comprising a flat blank of high grade steel including end portions disposed in alignment, 35 adapted to be riveted against the inner side of the runner sections 41, 42 as shown, the intermediate portion of the section 43 being offset upwardly, permitting the adjacent extremities of the runners to be turned upwardly as at 44, just within the offset portion 40 of the spring section 43. The mounting of the runner so constructed is the same as before described, and its action very much the same as that of the runners first described. 45

In employing my device where three or more standards are necessary to support the body of the sled upon the runners, a construction such as shown in Figs. 12 and 13 50 may be employed. In Fig. 12 there is shown a sled having four standards. The front standard A and the rear standard B, are constructed in the same manner as the standards before described herein, and mounted 55 in the same manner upon the bolsters, as well as the same connections employed between the standards and the runners. The intermediate standards C, however, instead of having the outer pivot openings and 60 centric slots 30 are provided in the upper flat portions with an elongated slot 45, extending at right angles to the mean direction of the runner, and a large bolt 46 is engaged through this slot and with the bolster

47 thereover, the bolt 46 being sufficiently 65 smaller in diameter than the width of the slot 45 to permit free movement of the standards laterally as well as pivotally with respect to the body of the sled. The steering connections are otherwise the same as before 70 described, and the manner of connecting the runners to the standards C is the same as the connections employed between the standards 75 12 and runners 10, as first mentioned. The super-flexile portion of the runners, however, is preferably located about midway of the length of the deck, as shown at 40^a although if found desirable this super-flexile portion may be located farther forward or to the rear, if desired without even impairing 80 the action of the device, these modifications being considered sufficiently obvious to require no illustration. The location of the portions 40^a may be decided by test, showing the highest efficiency. The super-flexile 85 portion of the runner is then preferably located between the two inner standards as at 40^a. In this way the two inner standards at each side move laterally when the runner is flexed, and in the construction shown in 90 Fig. 11 the central standard C is moved laterally by flexure of the runner.

If thought preferable the central bolsters 47 upon which the intermediate standards C are mounted may be fixed on the standards, 95 made free of the deck and slideable thereunder, in accordance with the customary practice in the front bolsters of present sled constructions, as shown in the patent to Allen, numbered 797,338, in Fig. 1. 100

In Fig. 5 a means for utilizing the links 18 in connection with auxiliary resilient elements to return the runners to normal position is shown. In this case, the links 18^b corresponding to the links 18 before described are mounted upon the forward bolster 14 and connected to the cross bar 20 in the same way as before described, but from their rear pivots arms 45 integral with the links are extended rearwardly and inwardly 110 beneath the deck 15, stopping short of the middle bar 17 a sufficient distance to swing clear of this bar under steering operation of the sled. The arms 45 are apertured at their extremities, and helical springs 46 of 115 suitable weight are engaged therewith and connected to the forward bolster 14 by means of eye bolts 47. The tensions of these springs being equal, they will tend to return the steering parts to normal position, 120 as will be readily understood.

In the operation of the sled, initial movement of the steering bar will produce simply a tilting movement of the runners, which, for slight turning movement may be found 125 sufficient to guide the sled. After a short degree of tilting movement, however, sufficient to produce the desired banking effect,

the lower part of the flange 33 of the runners strikes against one of the furcations of the foot, while the upper part of the flange 33 is held securely in the crotch of the foot, 5 preventing further tilting movement. From this point continued movement of the bar 28 will produce flexing action in the runners. A slight torsional strain of the runner also occurs permitting some lost motion, so to speak, between the forward end of the runner and the foremost standard. This lost motion due to the torsional yielding of the runner will be less in my device, however, than in the ordinary runner, because of the provision of the super-flexile portion 40 as described.

By having the runners hollow ground, as shown, the curved concave face intersecting the lateral edge faces of the runners, I am 20 able to make the sled runners function in the same manner as the runners of skates, for turning on icy surfaces, which is a feature that has never been before attained in sled runners.

It is found in the operation of the sled that the runners will tend to bow upwardly slightly in the middle, when flexed and this may be overcome by slightly bowing the runners downwardly, without detracting from 30 their normal efficiency.

What is claimed:

1. In a sled, a body including a deck, standards therefor having a fixed relation to the plane of the deck, runners mounted on the lower ends of the standards for lateral tilting movement thereon to incline their lower faces laterally in either direction from normal position, and means to turn the runners simultaneously.

2. In a sled, a superstructure, a runner mounted in supporting relation thereto at each side movable bodily at its intermediate part relatively to the superstructure, and including front and rear runner sections 45 and a resilient connection therebetween constructed to resist vertical flexure, and more yieldingly oppose lateral flexure and tending to hold the sections in longitudinal alignment.

3. In a sled, a superstructure, resilient flexible runners thereon including front and rear runner sections mounted for oscillation relatively to the superstructure for guidance of the sled, and a more flexible resilient element extending directly between and forming a connection between the front and rear runner sections.

4. In a flexible guiding runner sled, a body having legs thereon, a flexible runner 60 at each side, loose connections between the runners and legs whereby the runner may be tilted laterally, said runners being curved upwardly at their forward ends, and means to coact between the body and said forward

ends to flex the runners, whereby the runners will be tilted when flexed, for the purposes described. 65

5. A sled comprising a body, legs thereon having bifurcated divergent extremities, runners having upper edge portions set in the crotches of said bifurcations, fastening connections between the runners and legs constructed to permit lateral tilting of the runners, and means to tilt the runners.

6. In a sled having laterally tilting runners and means to tilt them, said runners being curved upward at their forward ends, a flexible cross piece having snug pivotal connections with the forward ends of the runners, said cross piece tending to retain the 75 runners in normal position.

7. A sled comprising a rigidly constructed body, longitudinally spaced legs mounted thereon for turning movement of all on a vertical axis, a flexible runner at each side 85 attached to the legs, said runners having an intermediate portion of much greater flexibility than their forward and rearward parts, and being free for lateral movement at said intermediate parts, and means coöperative between the body and forward ends 90 of the runners for flexure thereof.

8. In a sled of the character described, the combination of a body, legs pivoted thereon on vertical axes, a runner at each side 95 mounted on the legs for tilting movement, the runners, being projected forwardly and curved upwardly, and means coöperating between body and forward ends of the runners for lateral flexure thereof, whereby they 100 will be flexed and tilted.

9. In a sled of the character described a body, front and rear runner sections mounted thereunder for its support and for movement into angular longitudinal relation 105 and for lateral tilting movement to incline their lower faces laterally in either direction from normal, means to limit tilting movement of the runners, and means to move the forward upper part of the runners 110 laterally.

10. In a sled of the character described, a body, a flexible tiltable runner mounted thereon, means to limit tilting of the runner, and means to move the runner for tilting to its limit and beyond, including a laterally movable member connected pivotally to the runner above the axis of its tilting movement.

11. In a sled, a body, a plurality of standards, at least one being movable, a runner mounted on the standards for pivotal movement on a longitudinal horizontal axis whereby the runner may be tilted laterally, means to limit tilting movement of the runner on the standards and means to move one part of the runner laterally, including an eccentric connection. 120
125

12. In a runner of the character described, a body, a plurality of standards at each side, at least one being movable, said standards having divergent feet portions, a runner mounted between the furcations for lateral tilting movement, said furcations being disposed to limit tilting movement of the runner, an upwardly extended part on said

runner, and means to move said upward extension. 10

In testimony whereof I have affixed my signature in presence of two witnesses.
